(57) **CLAIM**

The ornamental design for a basketball, as shown and described.

DESCRIPTION

FIG. 1 is a front elevational view of the basketball showing our new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

The basketball player forming a part of the claimed design is a registered trademark of the National Basketball Association.

The broken line showing in FIG. 1 is for illustrative purposes only and forms no part of the invention.
